UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

DYNAMO-ELECTRIC MACHINE.

SPECIFICATION forming part of Letters Patent No. 269,761, dated December 26, 1882.

Application filed September 13, 1882. (No model.)

To all whom it may concern:

Be it known that I, EDWARD WESTON, a subject of the Queen of Great Britain, and resident of Newark, in the county of Essex and State of New Jersey, have invented certain new and useful Improvements in Dynamoelectric Machines, of which the following is a specification, reference being had to the drawings accompanying and forming a part of the same.

In another application filed by me I have described certain improvements in the construction of magneto or dynamo electric machines, the said improvements relating more particularly to the form of the frame and the mode of mounting the armature therein, and consisting in the combination, with the field-magnets or their pole-pieces, of solid projections supporting the bearings of the armature-shaft. My present invention involves the application of this invention, under conditions hereinafter specified, to a frame that possesses certain advantages over that described in my application referred to. The nature and purpose of the improvements will be hereinafter set forth.

In the drawings, Figure 1 is a view in side elevation of a machine embodying my improvements; Fig. 2, an end view of Fig. 1, with slight modifications.

Similar letters of reference indicate corresponding parts.

The general construction of the machine illustrated is as follows: Upper and lower field-magnet cores, A and B, are bolted to standards or side supports, C, and the latter are firmly bolted to a substantial base, D. The field-magnet cores A and B are wound with four coils, the direction of winding being such that the parts *a* and *b* form consequent poles of unlike polarity. Between the pole-pieces is mounted a cylindrical armature, E, on a shaft, F, which carries also a commutator, G, and a pulley, H. The specific character of these parts may, however, be considerably varied without departure from my present invention. For an understanding of the nature of the armature, and the plan of winding and connecting the same, reference is made to my former patents, No. 209,532, No. 259,618, and others. The lower magnet or core, B, is cast with a

projecting arm, K, which should be comparatively heavy for greater strength and stability. The opposite faces of the lower and upper pole-pieces are formed nearly square, or with slight grooves or ridges, and upon them is bolted a cap or brace, L, of brass or other non-magnetic metal, which affords a bearing for the armature-shaft close to the pulley H. The cap or brace L may be cast in one or two parts. It has strengthening-ribs *l l* and flanges *e*, by means of which it is bolted to the upper and lower poles. For large machines the caps L are required to be very strong and immovable, and to avoid the employment of a very large mass of metal stout braces or tie-rods N N, passing through lugs *n n* on the standards C and secured to the cap L, are employed. These braces may be four in number; or a greater or less number may be used. In Fig. 1 two only are employed, and usually this will be found sufficient. In very large machines, however, where the space between the two pole-pieces of the field-magnets and the distance between the faces of the poles and bearings of the shaft are necessarily great, four braces will be found to give the best results. To the end of the arm or projection K is bolted a casting, P, constituting a bearing for the commutator end of the shaft. The arm K is of such a length that this bearing will be beyond the commutator, or, in other words, so that the commutator lies inside the bearing. This construction is preferred, although the end of the arm K might itself be bored out to form a bearing for the shaft.

By the above-described mode of construction great stability is attained in even the largest machines. The truing of the bearings is greatly facilitated, all vibration or displacement by the pull of the driving-belt effectually prevented, and the armature exposed sufficiently for ready inspection or removal and for affording an increased circulation of air.

Though a complete machine embodying features of novelty other than those set forth is shown, such features are not specifically described herein, but will be made the subject-matter of other applications for Letters Patent.

Having now described my invention, what I claim as new, and desire to secure by Letters Patent, is—

1. The combination, in a dynamo-electric machine, with the upper and lower field-magnet cores, of a solid arm or projection extending from the lower core and affording a bearing 5 for the armature-shaft outside the commutator, substantially as set forth.

2. In a dynamo-electric machine, the combination, with field-magnet cores substantially such as described, of a solid arm or projection 10 extending from the lower pole-piece and affording a bearing for the commutator end of the shaft, and a non-magnetic cap or equivalent bolted to the faces of both pole-pieces and affording a bearing for the pulley end of the 15 shaft, as and for the purpose set forth.

3. The combination, with the field-magnets of a dynamo-electric machine substantially such as herein described, of a non-magnetic

cap bolted to the pole-pieces and affording a bearing for the armature-shaft, and brace or 20 tie-rods connected to the said cap and to the field-magnets, in substantially the manner herein set forth.

4. The combination, with the lower pole-piece of a dynamo-electric machine of the kind described, of a solid arm, K, extending out from the pole to a point beyond the commutator, and the casting P, constituting a bearing for the shaft, as set forth. 25

In testimony whereof I have hereunto set 30 my hand this 8th day of September, 1882.

EDWARD WESTON.
